UNITED STATES PATENT OFFICE.

GEORGE E. MATHER, OF EAST ORANGE, NEW JERSEY, AND BERTRAM BAILEY, OF NEW YORK, N. Y., ASSIGNORS TO WESTERN ELECTRIC COMPANY, INCORPORATED, OF NEW YORK, N. Y., A CORPORATION OF NEW YORK.

TRANSMITTER-SUPPORT.

1,272,692.

Specification of Letters Patent. Patented July 16, 1918.

Application filed March 2, 1917. Serial No. 152,066.

To all whom it may concern:

Be it known that we, GEORGE E. MATHER and BERTRAM BAILEY, citizens of the United States, residing at East Orange, in the county of Essex and State of New Jersey, and at New York, in the county of New York and State of New York, respectively, have invented certain new and useful Improvements in Transmitter-Supports, of 10 which the following is a full, clear, concise, and exact description.

This invention relates to adjustable telephonic transmission devices, and more particularly to adjustable supports for telephone transmitters. The invention is especially applicable to transmitters mounted on chest plates and supported on the body of the user in any desired manner.

One object of the invention is to provide 20 a support of simple and compact construction wherein the transmitter, when not in use, is positioned out of the way and protected by its support. Other objects are to provide a wide range of adjustment of the support to accommodate it to different users and to provide a construction which will not interfere with the freedom of movement of the user whether the transmitter is positioned for use or not.

30 This invention provides an adjustable telephone support for transmitters and the like wherein the transmitter is mounted on a movable arm pivoted to a second arm, which is in turn pivoted to a suitable base to 35 provide a wide range of movement for the transmitter in a plane perpendicular to the base. It further provides two pairs of arms pivoted together; one pair carrying the transmitter and the other pair being pivoted 40 to the base, the two pairs of arms being arranged to nest together to provide a compact structure and to house the transmitter to prevent damage thereto.

Referring to the drawings illustrating one 45 application of the invention, Figure 1 is a side elevation of the support mounted on the chest plate, part only of the chest plate being shown; Fig. 2 is a front elevation thereof; and Fig. 3 is a detailed view of the joint 50 provided between the base and the arms pivoted thereto.

In the form of invention shown, the support comprises a U-shaped member 1, which in practice would be secured to any suitable

base, a chest plate 2 being used in the present instance. The lugs 3 of the member 1 are perforated and studs 4 extend therethrough. Each of the studs 4 passes through the inner end of its respective curved arm 5, which is shown as mounted on the inner side 55 of its respective leg 3. Each of the studs has mounted thereon a bent plate 6 which engages the other side of its leg 3 and has lugs 7 which engage the notches 8 in its respective arm 5, as shown in Fig. 3. The 60 plate 6 is thus movable with its arm 5 and coacts therewith to provide a better bearing on its respective leg 3. The studs 4 are each provided with a pin 9 which fits into an opening 10 in its arm 5. The studs 4 are also 65 provided with split washers 11 and lock nuts 12, the outer ends of the studs being headed to prevent loss of the nuts 12. With 70 this construction all tendency of the split washers 11 to cut into the stationary parts is 75 eliminated, as the stud 4, arm 5, plate 6, washer 11, and nut 12 rotate as a single unit. By tightening the lock nuts 12, the arms 5 are engaged with the legs 3 with sufficient 80 protection to prevent accidental movement. The stud being fixed to the arms 5 is held 85 against rotation when it is desired to tighten the nuts and thereby facilitates quick adjustment. A variety of other means can obviously be utilized to prevent rotation of the stud if desired.

The outer ends of the arms 5 are perforated and held together by a stud 13 of similar construction to the stud 4 and held 90 against rotation by one of the arms 5 in a like manner. The stud 13 has two upwardly curved transmitter arms 14 pivoted thereto, the lower ends of the arms 14 lying between the outer ends of the arms 5. The stud 13 has a split washer 15 and lock nut 16, which 95 is held against loss by heading the end of the stud 13. A transmitter 17 is shown held between the upper ends of the arms 14 and pivoted thereto. To increase the friction both ends of the arms 5 are dished out 100 slightly at the points where they surround the studs 4 and 13 respectively. The arms 5 when taken together may be considered as a single U-shaped arm, as may also the arms 13, and obviously may be so constructed if 105 desired. The U-shaped transmitter arm is smaller than the outer U-shaped arm and nests therein when the parts are in closed

position. In this position the arms 5 and 14 inclose the transmitter 17 to a great extent and serve to protect it against injury.

A cord 18 carries the conductors to the transmitter through a bushing 19. A push button 20 is also shown on the transmitter but forms no part of the present invention. While shown as applied to a transmitter, the support can obviously be used to support receivers in a similar manner, if desired. The transmitter, instead of facing inwardly, as shown, might be arranged to face outwardly if the support on which it was mounted and the way in which it was 15 to be used made it more convenient.

When not in use the arms 5 and 14 are folded inwardly to bring the transmitter close to the base and inclose it within the arms, thus providing a simple and compact 20 arrangement as well as protecting the transmitter. When it is desired to use the transmitter it is drawn out and moved to the desired position, the friction being so proportioned as to permit movement when desired, 25 but sufficiently great to hold the transmitter in any position to which it is moved. The two sets of arms allow wide latitude of adjustment in both horizontal and vertical directions and the support is of such a compact 30 structure that it does not interfere with the freedom of movement of the user even with the transmitter in position for use. The pivotal movement of the transmitter 16 in the arms 14 is also desirable in providing 35 an increased range of adjustment.

What is claimed is:

1. An adjustable telephonic device comprising a base member, a U-shaped arm having its legs pivoted to said base member, a 40 second U-shaped arm, means pivoting the bases of said U-shaped arms together, and a telephonic transmission element mounted between the legs of said second arm; said first arm being broader than the second, 45 whereby the second arm may be positioned within said first arm.

2. An adjustable telephonic device comprising a base member, a U-shaped arm having its legs pivoted to said base member and 50 vertically movable relative thereto, a second U-shaped arm, means to pivot the bases of said U-shaped arms together, and a telephonic transmission element mounted between the legs of said second U-shaped arm; 5 said first arm being broader than the second, whereby the second arm may be moved within said first arm to position said tele-

phonic element within said arms and adjacent to said base member.

3. An adjustable telephonic device comprising a base member, an arm member, one of said members having a plate portion and the other member having portions engaging the opposite sides of said plate portion, a stud extending through said plate and plate 60 engaging portions to pivot said members together, means carried by said stud to vary the friction between said members, and a telephonic transmission element carried by said arm member. 70

4. An adjustable telephonic device comprising a base member, an arm member, one of said members having a plate portion and the other member having portions engaging the opposite sides of said plate portion, a stud extending through said plate and plate 75 engaging portions to pivot said members together, means carried by said stud to vary the friction between said members, means holding said stud against rotating movement relative to said engaging portions, and a telephonic transmission element carried by said arm member. 80

5. An adjustable telephonic device comprising a base member having an upstanding ear, an arm pivoted to said ear and having a portion engaging one side of the ear and another portion movable with said first portion engaging the opposite side of said ear, a stud pivoting said arm to said ear, 85 means carried by said stud to vary the friction between said arm and ear, means holding said stud against rotating movement relative to said arm, and a telephonic transmission element carried by said arm. 90

6. An adjustable telephonic element comprising a base member having an upstanding ear, an arm having a recess therein engaging one side of said ear, a separate plate engaging the other side of said ear and having a projection to engage said recess, a stud pivoting said arm and plate to said lug, said stud being rotatable with said arm and plate, means carried by said stud to vary the friction of said arm and plate with said 95 ear, and a telephonic transmission element carried by said arm. 100

In witness whereof, I hereunto subscribe my name this 23rd day of February, A. D. 1917.

GEORGE E. MATHER.

In witness whereof, I hereunto subscribe my name this 1st day of March, A. D. 1917.

BERTRAM BAILEY.
